RUBBERIZED BELTING AND METHOD OF
MAKING THE SAME

Hunter McKay, Belmont, Mass., assignor to Boston Woven Hose & Rubber Company, Cambridge, Mass., a corporation of Massachusetts

Application April 1, 1938, Serial No. 199,405

8 Claims. (Cl. 154—4)

This invention relates to rubberized belting of the type which includes in its structure alternate layers or plies of rubber and textile fabric vulcanized or cured under pressure.

5 The invention consists in belting of this type characterized by a novel surface configuration, viz., the rubber surface layer being provided with a multiplicity of depressions displacing the threads of one or more textile plies with a pile effect thus improving the traction surface of the belting and tending to prevent the belting from wearing smooth in use.

It has been the practice heretofore to emboss the surface of belting, particularly leather belting, in order to give its traction surface a vacuum cup effect, but such embossing has been superficial and has not modified the internal structure of the belting. My invention, on the contrary, contemplates a molding of the belting in which the underlying textile ply or plies have their threads displaced by pressure transversely to the plane of the fabric so that they tend to approach an upright position in the surface layer of the belting, extending as loops in the projecting portions, and being depressed below the depressions formed in the rubber surface layer. In some cases the molding step may uncover the fabric threads in the bottom of all or some of the depressions in the surface layer of rubber, and in other cases the molding step may be less severe, but it is desirable, in accordance with my invention, to displace the threads to some degree from the normal flat plane of the fabric so that in wear the upstanding threads will be exposed in points separated from each other by a vulcanized rubber filler.

10 The design of the surface is of secondary importance. It may be a regular geometric design or it may be irregular, for example, a design produced by a coarse sand paper matrix.

15 The invention includes within its scope the novel process herein disclosed as a preferred manner of producing the novel belting of my invention.

The nature of the invention will be best understood and appreciated from a consideration of the accompanying drawings illustrating a preferred embodiment of the belting and one step in the process of its manufacture. In the drawings,

20 Fig. 1 is a diagrammatic view in section illustrating the step of molding or embossing one surface of the belting;

Fig. 2 is a fragmentary plan view of the belting, a portion being shown in magnified scale,

Fig. 3 is an enlarged view in side elevation of a portion of a belt cut along the line 3—3 of Fig. 2,

Fig. 4 is a diagrammatic view in section illustrating the step of molding both surfaces of the belting,

Fig. 5 is a view in side elevation on an enlarged scale showing the effect of the molding 10 operation and illustrating a splice, and

Fig. 6 is a plan view of Fig. 5, part being cut away.

As indicated in Fig. 3 the particular type of belting selected for illustration comprises four 15 plies 10 of woven textile material embedded in and spaced by five layers 11 of rubber composition. In manufacturing such belting the rubberized fabric layers are coated with uncured rubber and are then assembled and subjected to 20 pressure and heat so that they are vulcanized into a solid integral mass. A commercial process of making belting of this general type is disclosed in U. S. Letters Patent No. 2,093,904 granted September 21, 1937, on an application of John 25 M. Bierer. The said patent also discloses apparatus for carrying out the process of manufacture and I contemplate employing the same apparatus in the production of the novel belting 30 of my invention, although it is in no sense limited to that or to any specific apparatus.

As in the said patent the assembled layers of rubber and fabric are subjected to heat and pressure between a large cylinder 20 and a steel pressure band 22 operating as suggested in Fig. 1. The cylinder 20 is modified to carry out the process of my invention by being provided with a cylindrical embossing surface herein shown as comprising geometrically arranged ribs 21 disposed at right angles to each other and separated by pyramidal recesses. The belting material is fed about the periphery of the heated cylinder 20 under severe pressure of the steel band 22. In its progress about the cylinder the ribs 21 embed themselves completely in the material of the belt, displacing the rubber of the surface layer and also the underlying textile ply in the configuration shown in Figs. 2 and 3, that is to say, the entire surface of the belting is criss-crossed with ribs 12 disposed at right angles to each other and defining pyramidal depressions in the bottom of each of which is exposed or substantially exposed one or more threads of the uppermost textile layer 11 in the body of the belting. In

- addition to this visible evidence of displacement the molding operation causes a portion of the threads of the textile layer to be displaced upwardly into the tapering ribs of the surface configuration. In other words the individual threads are flattened in the valleys and their curvature intensified in the rib portions of the belting, imparting somewhat of a pile effect to the fabric. Thus in a single step process the belting material is not only cured and vulcanized but has imparted to it a surface configuration of the character described and a structural modification resulting in improvement of the traction and wearing quality of the product.
- 15 As shown in Figs. 4 and 5, I also contemplate molding both the upper and lower surfaces of the belting, and this may be accomplished by placing a flexible mold 24 on the surface of the pressure band 22, whereby the belting 25 is molded on both 20 surfaces. The mold 24 may be constructed of any suitable flexible material. The result of such treatment is illustrated in Fig. 5 wherein the upper and lower textile plies 26 and 27 are sharply peaked at various points and the center plies 28 are considerably flatter and more gently curved. The splice is indicated by the staggered breaks at 29 in the textile plies and shown to be in a line oblique to the face of the belting. Belting molded on both surfaces is useful for driving many types of machines such as 25 spindle machines. Furthermore, the double molding operation serves the additional advantage of clamping down the splice from both surfaces.
- It will be understood that the outstanding advantage presented by belting of the character above described is that its surface has a higher coefficient of friction between the belting and the pulley or between the pulley lagging and belting than has been available heretofore in commercial conditions, and this advantage continues as the belting wears down in use. Therefore, the belting of my invention allows the transmission of more power or the carrying of greater load with less slippage and lower initial or total tension in the installation than heretofore. Besides increasing the efficiency of the belting, this factor tends also to increase its useful life since both slipping and high tension are detrimental in this respect.
- 50 In addition to the greater coefficient of friction, the roughened surface when applied to endless belts is of material benefit in holding down the lip of the splice. The conventional belt is made endless by joining staggered ends of the plies of two or more pieces of rubberized fabric and vulcanizing the body of the belting. The splice is normally the weakest part of an endless belt, there being a great tendency for the extreme end or lip of the splice to curl up. The molding or embossing above described tends to clamp or bind down the splice so that it is less likely to curl or open so readily. I desire it to be understood that my invention includes in its scope a belt having 55 molded pyramidal depressions limited to that portion of the belt which contains the splice.
- Another advantage of the belting of my invention is in respect to appearance. The conventional smooth friction surface belting, particularly that made with light colored rubber compounds, 60 reveals clearly the nature of the fabric weave as well as any imperfections or defects therein. On the other hand, the roughened surface conceals these characteristics and allows the production of belting within commercial limits of any desired 65 appearance regardless of the character of the

fabric used in its structure, and the fabric weave does not become apparent as the working surface or surfaces wear down.

The life of the belting is also increased because the embossing or molding action tends to to increase or retain the natural crimp of the textile fabric. In the case of woven fabrics this is true of both the warp and filler. In rubberized belting as heretofore constructed there is a tendency to spread the belting widthwise in the vulcanizing press and this spreading reduces the already light initial crimp in the fabric. The rough molded or embossed surface tends to retard this spreading and therefore increases the crimp especially in the 10 filler.

15 In rubberized belts as heretofore constructed with smooth surface, the textile fibres of the fabric lie more or less parallel with the surface of the belting. With normal wear and slippage these belts tend to become slick and shiny on the surface with a serious resulting loss in traction. The molded or embossed belting on the other hand, tends to peak certain portions of the fibres so that after some wear a pile-like surface is produced. The treatment also tends to prolong the high coefficient of friction in the belting. It will be noted also that the embossed or molded cavities serve for retaining belt dressing should such dressing be used.

Having thus disclosed my invention and described a preferred manner of practicing it, I claim as new and desire to secure by Letters Patent:

1. Rubberized belting comprising alternate 35 layers of rubber and textile fabric including a surface layer of rubber with indentations molded therein of sufficient depth to cause displacement of the fabric threads transversely with respect to the plane of the fabric toward the indented surface of the belting.

2. Rubberized belting comprising alternate layers of rubber and textile fabric including a surface layer of rubber with indentations and projections therein, the threads of the uppermost fabric layer being deflected downwardly beneath the indentations and upwardly into the projections of the belting.

3. Rubberized belting comprising superposed layers of rubber and woven fabric including a surface layer of vulcanized rubber having a series of indentations therein, each of which substantially exposes a thread of the fabric in its bottom and contains an upwardly looped thread in its side walls.

4. The process of making rubberized belting of superposed layers of rubber and woven fabric, which is characterized by the step of molding indentations in a rubberized surface layer of the belting and simultaneously uncovering spaced threads of the underlying fabric to render them visible through the overlying rubber layer.

5. Rubberized belting comprising alternate layers of rubber and textile fabric including upper and lower surface layers of rubber with indentations molded therein of sufficient depth to cause displacement of the fabric threads transversely of the surfaces of the belting.

6. The process of making rubberized belting of superposed layers of rubber and fabric, which is characterized by the step of molding indentations in the upper and lower rubberized surface layers of the belting and simultaneously uncovering spaced threads of the underlying fabric in the bottom of the respective indentations.

7. The process of improving the traction and wearing qualities of rubberized belting composed of layers of rubber and fabric, which is characterized by simultaneously vulcanizing the belting, causing the threads of the outermost fabric layers to be peaked toward the working surface by depressing the fabric at spaced locations and causing displacement of the outer rubber layer substantially uncovering short lengths of the
- 5
10. thread of the underlying fabric layer.
8. The process of making rubberized belting of

superposed layers of rubber and fabric, which is characterized by simultaneously carrying out the steps of vulcanizing the belting, molding indentations in its working surface, depressing and uncovering the thread of the fabric at the bottom of the respective indentations and causing the thread between said indentations to be displaced transversely with respect to the plane of the fabric.

HUNTER McKAY.
